UNITED STATES PATENT OFFICE.

FRANK ATHERTON HOWARD, OF ELIZABETH, NEW JERSEY, ASSIGNOR TO STANDARD DEVELOPMENT COMPANY, A CORPORATION OF DELAWARE.

ART OF DISTILLING OILS.

Application filed February 14, 1921. Serial No. 444,682.

The present invention relates to the distillation of oils under pressure whereby a pyrogenetic conversion of higher boiling point oils into lower boiling point oils such as gasoline is effected, and the simultaneous removal and recovery of the constituents of natural gas ordinarily designated as natural gas gasoline.

In carrying out the present invention, the pressure distillation for the production of light hydrocarbon oils such as gasoline is carried out in the usual manner, for example, at a pressure of 4 to 7 atmospheres, the condensation of the light oils produced being effected under the same pressure prevailing in the still. The natural gas, from which the gasoline constituents are to be removed and recovered, is introduced into the vapor space of the still or the vapor apparatus connected thereto, and passes through the vapor apparatus and the condenser under the pressure prevailing therein. The gasoline constituents of the natural gas are condensed or absorbed in the process during the condensation of the products of conversion from the pressure still, and the combined products are collected. If desired, the uncondensed gas escaping may be passed through an absorbing system in which the higher hydrocarbons are absorbed in a suitable hydrocarbon liquid, in which case the absorbing liquid may subsequently be deprived of the absorbed hydrocarbons by introducing it into the pressure still.

Means suitable for carrying out the present invention are illustrated in the accompanying drawings, in which—

Figure 1 presents an arrangement of apparatus suitable for use in connection with the invention, and

Figures 2 and 3 illustrate modified arrangements of apparatus likewise suitable for carrying out the invention.

The individual pieces of apparatus are illustrated diagrammatically. Referring more particularly to Fig. 1, the numeral 5 indicates the bulk supply container of an oil still, communicating by conduits 6 and 7 with the upper and lower tube headers 8 and 9 respectively, between which the upwardly inclined tubes 10 extend. The tubes 10 are mounted in furnace 11, the oil being heated therein. The numeral 12 indicates a gas holder, which receives gas from a nat-

ural gas field through a conduit 13 and the wet gas produced during the refining of crude petroleum oil through pipe 14.

The still is provided with a vapor line 15, preferably arranged in an upwardly inclined position, and leading to a dephlegmator 16, illustrated as an air cooled tubular condenser. The vapors from the still which condense in the vapor line 15 and the dephlegmator 16 return to the still through the former. The lighter vapor products pass on through pipe 17 and condenser 18 to the receiver 19, in which the condensed light products are collected and from which they may be withdrawn through discharge pipe 20.

The operation of the process is best considered in connection with the reduction and refining of crude petroleum. The gas oil or fuel oil distillate produced in such refining and having a density of, say, 32° Baume, is charged into the pressure still, and is heated to effect distillation while a pressure of say 4 to 7 atmospheres is applied through the system. Lighter hydrocarbons are produced, and the vapors issuing from the still pass through the vapor system above described. During the distillation, wet gas is pumped from gas holder 12 by pump 21 through distributing pipe 22 into the vapor phase system of the still, for example, into the container 5 above the liquid level therein. The gas mixes with the distillation vapors and its gasoline-like constituents, which are to a considerable extent so much more volatile than the gasoline of commerce that they are not condensed at the same temperature, blend with heavier constituents of the vapors and are condensed in the gasoline condenser 18.

The uncondensed gas issuing from receiver 19 passes through pipe 23 into the absorber 24, where it is scrubbed with the light gas oil distillate from the crude petroleum, which is supplied to the absorber through the line 25. The unabsoed gas passes out through pipe 26 to a main or reservoir. The absorber liquid, with its absorbed light hydrocarbons issues through pipe 27 and is conducted into the vapor system of the still, where the light hydrocarbons are yielded up, passing through the condenser where the condensable constituents increase the gasoline yield, while the absorber liquid

forms a feed stock to maintain the proper level of the stock undergoing distillation in the still.

In Figs. 2 and 3 arrangements of apparatus are shown in which low pressure absorbers as well as high pressure absorbers are employed, in Fig. 2 the absorbers being shown arranged in parallel and in Fig. 3 arranged in series.

10 Referring more particularly to Fig. 2, the gas holder 28 is fed with wet gas from the field through line 29 and from the refinery through line 30. The wet gas passes from the gas holder 28 through line 31 to the low pressure absorber 32, into which the absorbent liquid, which is the feed stock for the pressure stills, enters through the line 33. The gas, after absorption of its gasoline constituents, issues from the low pressure absorber 32 through line 34 to the line 35, which conducts it to the dry gas holder 36. The absorbent liquid issuing from the low pressure absorber is pumped through line 37 into the feed line 38 leading to the pressure stills 39. The distillation gases from the pressure stills 39, each of which is of the same general character as that shown in Figure 1 and is provided with a dephlegmator, pass through the high pressure line 40 into the high pressure absorber 41, where they are treated by the pressure still feed stock entering through the line 42. The treated gas passes out of the high pressure absorber 41 through the line 43 leading to the dry gas line 35, through which it is conducted to the dry gas holder 36. From the dry gas holder suitable mains 44 and 45 conduct the treated gases to the refinery and to the field respectively.

40 In the arrangement of apparatus shown in Fig. 3, the low pressure and high pressure absorbers are arranged in series, the feed stock for the pressure stills, which is used as the absorbent liquid, passing successively 45 through the low-pressure absorber and the high pressure absorber. Referring more particularly to this figure, the numerals 46 and 47 indicate the lines by which the wet gas from the fields and from the refinery 50 respectively is conducted to the gas holder 48. From this gas holder wet gas passes through line 49 into the low pressure absorber 50, in which it is treated by the pressure still feed stock entering through line 51. 55 The gas issuing from the absorber 50 is forced through line 52 into the dry gas line 53, which leads it to the dry gas holder 54. The absorbent liquid passing out of the low pressure absorber 50 is forced through line 60 55 into the high pressure absorber 56, in which it acts to absorb the gasoline constituents from the gas issuing from the pressure stills 57. The absorbent liquid passes out of the high pressure absorber 56 through line 65 58, which leads it into the pressure stills.

The distillation gas from the pressure stills passes through line 59 into the high pressure absorber 56, in which it is treated as above described. The treated gas passes out through line 60 into the dry gas line 53, which conducts it into the dry gas holder 54.

It is readily apparent that batteries of pressure-stills and associated apparatus may be employed and a uniform pressure control may be applied to the entire system.

Although the present invention has been described in connection with the details of an illustration of its employment, it is not intended that these details shall be regarded as limitations upon the scope of the invention, as set forth in the accompanying claims.

I claim:

1. The process of oil distillation for the production of light hydrocarbon oils which consists in subjecting heavier hydrocarbon oils to distillation under pressure, introducing at a temperature not substantially above atmospheric natural gas containing gasoline constituents into the vapors issuing from the distilling oils, subjecting the mixed vapors to a partial condensation, returning the condensate thereof to the distilling oil and condensing the desired light hydrocarbons from the vapors under the same pressure.

2. The process of oil distillation for the production of light hydrocarbon oils which consists in subjecting heavier hydrocarbon oils to distillation under pressure, introducing at a temperature not substantially above atmospheric natural gas containing gasoline constituents into the vapors issuing from the distilling oils, refluxing the mixed vapors and returning the fractions thereof heavier than the desired light hydrocarbons to the distilling oil and condensing the light hydrocarbons from the vapors under the same pressure.

3. The process of oil distillation for the production of light hydrocarbon oils which consists in subjecting heavier hydrocarbon oils to distillation under pressure, condensing the desired light hydrocarbons from the vapors under the same pressure and introducing natural gas containing gasoline constituents into the vapors issuing from the distilling oils prior to condensation thereof, said natural gas being at a temperature not substantially above atmospheric, contacting the uncondensed vapors and gas with a hydrocarbon oil heavier than the condensed light hydrocarbon oil, thereby absorbing the gasoline constituents from such vapors and gas, and introducing the absorbing liquid with its absorbed light hydrocarbons into the pressure still.

4. The process of oil distillation for the production of light hydrocarbon oils which consists in subjecting heavier hydrocarbon oils to distillation in a still under pressure, introducing natural gas containing gas-

oline constituents at a temperature not substantially above atmospheric into the vapors from the distilling oils, subjecting the mixed vapors to a partial condensation, condensing the uncondensed vapors under the pressure of the still, contacting the remaining uncondensed vapors and gas with a hydrocarbon oil heavier than the condensed light hydro-

carbon oil, thereby absorbing the gasoline constituents from such vapor and gas, and 10 passing the absorbing liquid with its light absorbed hydrocarbons together with the condensate from said partial condensation into contact with the mixed vapors issuing from the still and into the pressure still.

FRANK ATHERTON HOWARD.
